UNITED STATES PATENT OFFICE.

JOHNSTON TURNER, OF SHEFFIELD, ENGLAND.

DOWEL.

1,419,652.

Specification of Letters Patent. Patented June 13, 1922.

Application filed September 7, 1921. Serial No. 498,982.

To all whom it may concern:

Be it known that I, JOHNSTON TURNER, a subject of the King of Great Britain and Ireland, and residing at 28 Plumbers 5 Road, Sheffield, in the county of York, England, have invented certain new and useful Improvements in or Relating to Dowels, of which the following is a specification.

This invention relates to dowels, that is 10 to say, devices adapted to be secured to one part and to project into engagement with a recess or socket in another part for the purpose of retaining the two parts in correct relation to each other. The invention 15 is particularly useful for connecting the parts of wooden patterns and core boxes or for connecting patterns or parts thereof to pattern-supporting devices, such as the pattern plates of moulding machines, 20 but is not limited to such use.

A hollow drawn dowel-pin has been proposed comprising a cylindrical dowel portion closed at its outer end and provided at its open end with four long angular 25 prongs. The prongs were forced into one part and marking of the counterpart was effected by pressing the closed outer ends of the dowels against the counterpart to cause small caps on the outer ends of the 30 dowels to make depressions in the counterpart.

The object of the present invention is to provide an improved dowel and with this end in view the invention consists in a 35 dowel comprising a body portion having an axial bore extending therethrough and small prongs for temporarily securing the body portion in position and extending laterally of and beyond one end of the body 40 portion, in combination with a headed screw or pin, the point of which is adapted to project from the pronged end, the head of the screw or pin being adapted to engage the opposite end of the body so as firmly 45 to secure the body, after it has been temporarily positioned by means of the prongs.

Referring now to the accompanying drawings:—

Figure 1 is a plan view of a form of 50 improved dowel;

Figure 2 is a sectional view on line A—A of Figure 1 and showing the dowel in use on a core box or the like, and

Figure 3 is a sectional elevation of a 55 slightly modified form of the improved dowel.

Referring to Figures 1 and 2 the reference numeral 1 indicates the body portion of the dowel, which in this instance is in the form of a metal sleeve. One end of 60 the body portion is formed with three prongs 2, which in the illustrated example are shown as claws projecting slightly outwardly and beyond the end of member 1. It will be understood that any suitable number 65 of prongs may be employed. A suitable form of screws for co-operating with the body 1 is shown at 3. The screw 3 preferably has a rounded head 4 which is of the same diameter as the outer periphery of the body 1, and an unthreaded portion 5 of substantially the same length and diameter as the aperture of the body 1.

It will be understood that the body portion and screw may be made of any suitable metal, preferably iron or brass.

The body portion may be made to suit any of the standard sizes of headed screws. The form of prong or claw illustrated in Figures 1 and 2 is suitable for dowels of 80 the smaller sizes.

A slightly modified form of prong is shown at 6 in Figure 3, in which the prongs are formed entirely beyond the end surface 7 of the body portion, so as to allow the 85 prongs of the dowel to be forced entirely below the surface of the material of the core box or the like. This form of prong is especially suitable for the larger sizes of 90 dowel.

The improved dowel is put into position as follows:—

A recess or bore 8 is made in the edge face of one part 10 of, for example, a core box, and a metal socket 9 is driven into recess 95 in the usual manner. The dowel is introduced into the recess 8. The second part or half 11 is now positioned in the desired relation with respect to the part 10, and the two parts of the box are forced towards each 100 other by pressing or hammering. The prongs 2 are thus caused to enter the material of part 11 of the box. When the part 10 of the box is removed from the part 11, the dowel, being now secured to the part 11, 105 leaves the recess or socket 8 in the part 10, and the dowel may then be secured in position by the screw 3.

By loosely inserting the dowel in one part and then transferring it to the co-operating 110 part of the box in the manner above described, all risk is eliminated of the two

parts being out of correct alignment or relation with each other when the dowels are brought into engagement with their respective sockets.

5. If desired the body portion may be countersunk at both ends, and the screw-head shaped to fit the countersunk recess at the upper end of the body.

With the present invention patterns are 10 not mutilated with centre bit holes and are more readily attached to a pattern-plate owing to the fact that the prongs hold the dowels in position until they are secured by the screws.

15. It will be understood that any suitable size or shape of body piece and screw may be employed.

Having now described my invention, what I claim as new and desire to secure by Letters Patent is:—

20. 1. A dowel comprising a body portion hav-

ing an axial bore extending therethrough and small prongs for temporarily securing the body portion in position and extending laterally of and beyond one end of the body 25 portion in combination with a headed screw or pin, the point of which is adapted to project from the pronged end, the head of the screw or pin engaging the opposite end of the body so as firmly to secure the body after 30 it has been temporarily positioned by means of the prongs.

2. A device as claimed in claim 1, wherein the prongs are formed entirely beyond the plane of the end surface of the body portion, 35 whereby said prongs may be forced entirely below the surface of the member to which the dowel is applied.

In testimony whereof I have signed my name to this specification.

JOHNSTON TURNER.
